UNITED STATES PATENT OFFICE.

WILLIAM FRANK HARVEY, OF TORONTO, ONTARIO, CANADA.

DISPLAY BOX.

1,416,465.

Specification of Letters Patent. Patented May 16, 1922.

Application filed June 7, 1920. Serial No. 337,026.

To all whom it may concern:

Be it known that I, WILLIAM FRANK HARVEY, a subject of the King of Great Britain, and resident of the city of Toronto, county 5 of York, Province of Ontario, in the Dominion of Canada, have invented certain new and useful Improvements in Display Boxes, described in the following specification and illustrated in the accompanying drawings, 10 that form part of the same.

The principal objects of this invention are to devise a form of box which will enable the goods contained therein to be displayed to advantage being supported rigidly 15 in an inclined position.

A further object is to devise a box with a cover constructed so as to firmly secure the contents in place and which may be turned back in such a manner as to rigidly support 20 the box in the raised position and also rigidly support a display card at the upper end.

The principal feature of the invention consists in the novel formation of the box 25 whereby the cover is formed with side flaps adapted to securely lock the sides and to be turned back and lock securely in the opened position to elevate one end of the box and to support a display portion on the upper 30 end.

In the drawings, Figure 1 is a plan view of the blank.

Figure 2 is a perspective view of the box shown in the closed position and Figure 3 is 35 a perspective view showing the box with the cover turned back and supporting the box in a raised position.

Referring to the accompanying drawings it will be seen that the blank is formed from 40 a substantially rectangular piece of card having a longitudinal centre strip 1 which forms the bottom, ends and top. The inner sections 2 are creased across the strip 1 and having the laterally extending tabs 3 and 45 between the tabs on either side are arranged the side members 4 which are separated from the tabs 3 to form a part of the body 1, being creased along the same longitudinal lines as the tabs.

50 The outward edges of the members 4 are creased longitudinally at the same depth as the width of the tabs 3 and the outer edges are formed with rounded lugs 5. The tabs 3 are formed with slits 6 cut therein 55 adapted to seal the lugs 5 when the box is folded.

Curved slits 7 and 8 are formed in the side members 4 arranged in angular positions for a purpose which will hereinafter appear.

The central portion 1 extends outwardly 60 from one end to form the cover 9 and at the other end this cover is provided with the side flaps 10 creased along the longitudinal line of the main strip 1 and having the lug portions 11 which are adapted to enter the 65 slits 7 and 8.

The cover portion 9 is preferably cut through on its longitudinal centre to form a tab 12 and the cover is creased transversely from the base of the tab cut 12. 70

In forming the box the ends 2 are turned upwardly and the tabs 3 are turned inwardly. The sides 4 are then turned upwardly along the longitudinal crease and the upper portion of the sides is bent over 75 the tabs 3 and the lugs 5 are inserted in the slits 6, thus forming the body of the box into a strong structure.

The top 9 is then bent over close to the box as shown in Figure 2, with the tabs 11 inserted in the slits 7. These tabs hold the cover 9 securely down upon the top of the box and also bind in the sides of the box and a very secure package is made. 80

When it is desired to display the 85 contents of the box the free end of the cover is bent upwardly and the flaps 10 spring out to release the tabs 11 from the slits 7. The cover is then raised up and bent backwardly on the creased line 13 so that the 90 portion 14 extends upwardly at the end of the box as shown in Figure 3 with the display tab 12 projecting from the top. The remaining portion of the cover folds back against the end of the box and projects below it. 95

The side lugs 10 of the top are bent back in the opposite direction so that the lugs 11 may be entered into the slits 8 in the sides of the box. When the lugs are thus inserted the cover support is secured to form 100 a rigid support for holding the box in the raised position so as to display the goods therein.

What I claim as my invention is:— 105

1. A display box, comprising, a body portion having slits in sides, a cover hinged to one of the ends of the body portion and having side flaps bent downwardly and each formed with lugs adapted to enter said slits 110 to hold the cover locked in its closed position, said cover having a transverse crease

intermediate of its length and adapted to be turned back to lie against the end of the box and to project above the top of the edge, the creased portion projecting above the edge 5 and the under projecting below the bottom and adapted to be secured in such position.

2. A display box, comprising, a body portion and a cover formed of one piece, the sides of the body portion each having a pair 10 of angularly arranged slits, the cover having a pair of side flaps at the outer end, said side flaps having lug ends at the ends adjacent to the body portion adapted to enter

and engage the slits in the body, said cover being transversely creased intermediate of 15 its length and adapted to be folded, the portion adjacent to the body being adapted to lie in alignment with the end and project above the top of the box when the cover is folded back, the lugs of the said cover being 20 adapted to engage the other pair of slits in the body to hold the cover against the end of the box and to support the body in the raised position.

WILLIAM FRANK HARVEY.
